ELECTRONIC BONDING MACHINE

Hans Hacklander, Linden, N. J., assignor to The Singer Manufacturing Company, Elizabeth, N. J., a corporation of New Jersey

Application October 20, 1949, Serial No. 122,421

3 Claims. (Cl. 219—47)

1

This invention relates to machines for bonding together superposed plies of dielectric materials by passing the plies through a radio-frequency field to produce heat in the plies and applying pressure to the plies while they are within the field.

One of the objects of this invention is to provide an improved machine for making tubular articles such as sleeves of raincoats and the like, which machine feeds the material off the free end of a tubular shaped arm and the feeding mechanism is actuated by adjustable belts arranged within the confines of the arm.

Other objects of this invention are the provision of improved means for adjusting the driving belts which actuate the feed-wheels and for conducting the radio-frequency current to the electrodes.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is a top plan view of an electronic bonding machine embodying the invention.

Fig. 2 is a left side elevation of the machine shown in Fig. 1, the laterally extending tubular work-supporting arm being shown in section and the face-plate of the bracket-arm removed to expose the operating parts.

Fig. 3 is a vertical sectional view taken substantially along the line 3—3 of Fig. 1.

Figs. 4 and 5 are fragmental sectional views taken substantially along the lines 4—4 and 5—5 of Fig. 1.

In the embodiment of the invention selected for illustration, the machine comprises a standard 10 carrying an overhanging arm 11 which terminates in a hollow-head 12. Journaled in bearings 13 and 14 in the arm 11 is a main shaft 15 having a combined pulley and hand-wheel 16 secured to its out-board end. The pulley 16 may be connected to any suitable source of power for the purpose of rotating the shaft 15.

The hollow-head 12 is provided with vertically aligned bearings 17 and 18 (Fig. 2) in which an endwise reciprocatory electrode carrying bar 19 is journaled. The bar 19 is urged downwardly by a coil compression spring 20 which surrounds the bar 19 and reacts between the upper bearing 18

2

and a split collar 21 adjustably clamped to the bar 19. Clamped to the upper end of the bar 19 is a split collar 22 carrying a laterally extending pin 23 having a roller 24 journaled thereon. The roller 24 is located above and cooperates with an eccentric 25 fixed on the free end of the main shaft 15. From the above it will be understood that, when the shaft 15 is rotated, the eccentric 25 will engage the roller 24 and raise the electrode bar 19 against the action of the spring 20 through a part of each revolution of the shaft, and will then move away from the roller and permit the spring 20 to force the bar downwardly during the remaining portion of the revolution of the eccentric.

For the purpose of adjusting the maximum downward movement of the spring depressed electrode-bar 19, a screw 27 is threaded into a boss 28 formed in the head 12. The upper end of the screw 27 extends through a suitable opening in the upper part of the head and is formed with a screw-driver slot for the purpose of quick adjustment. The screw 27 carries a washer 29 adjustably held in position on the screw 27 by the nuts 30 disposed on opposite sides of the washer. As shown in Fig. 2 the peripheral marginal edge of the washer 29 is arranged to underlie the lower end of the split collar 22 fixed on the bar 19 and the position of the adjustable washer 29 determines the lowest position to which the spring depressed electrode bar 19 may descend.

The standard 10 is rigidly associated with and mounted upon a U-shaped bed including a supporting arm 31 (Fig. 1) extending forwardly from the standard, a laterally extending hollow horizontal carrier-arm 32 joined at one end to the forwardly extending arm 31 and carrying at its other end the hollow horizontal work-supporting arm 33 which is joined to and is substantially coplanar with the arm 31 and terminates at its free end below the hollow-head 12. The carrier-arm 32 rises above the level of the arms 31 and 33 and the bottom wall 32' of the carrier-arm (Fig. 2) is disposed slightly below the level of the upper walls of the arms 31 and 33. This construction provides clearance space at the underside of the arm 32 to facilitate handling of the work.

Journaled beneath the standard 10, in a bearing 34 formed on the forwardly extending arm 31 (Fig. 1), is a short shaft 35 arranged parallel with the main shaft 15. The rotary shaft 15 imparts intermittent step-by-step rotary movement to the shaft 35 through a mechanism comprising an eccentric 36 secured upon the main shaft 15 (Fig. 3), a block 37 surrounding the eccentric, and a

connecting rod 38 having its upper forked end 39 engaging the sides of the block 37 and its lower end pivotally connected, at 40, to a laterally extending arm 41 of a one-way clutch 42 which is secured upon the shaft 35. The clutch 42 is the same as that disclosed in my U. S. Patent No. 2,277,971 of March 31, 1942, to which reference may be had for a detailed description of the internal mechanism of the clutch.

Adjacent its upper end, the connecting rod 38 has pivotally connected to it, at 43, one end of an anchor link 44, the other end of which is pivotally connected at 45 to a normally stationary crank-arm 46 having its upper end fulcrumed on the frame of the machine. The free lower end of the crank-arm 46 is provided with an open-ended slot 47 which receives a pin 48, carried by one arm of a feed regulating bell-crank lever 49 fixed on a pivot-stud 50 carried by the standard 10. The other arm of the bell-crank lever 49 extends laterally to a point between spaced cams 51 and 52 carried by ends of parallel stub shafts 53 and 54 which extend through suitable bearing bosses formed on the standard 10. For the purpose of adjusting the position of the cams 51 and 52, each of the shafts 53 and 54 has secured to the ends protruding from the standard, knobs 55 and 56, respectively. A tension spring 57 has one of its ends anchored to a stud 58 carried by the standard and its other end secured to an arm 59 carried by the pivot-stud 50. This spring urges the bell-crank lever 49 in a clockwise direction about its pivot and thus constantly urges the free end of the bell-crank lever 49 against the upper cam 51. From the above, it will be understood that an oscillating movement is imparted to the arm 41 of the clutch 42 by the movements of the block 37, which is actuated by the eccentric 36. The back-and-forth movements of the block 37 cause the connecting rod 38 to swing about its pivot 43. Due to the pivotal connection of the anchor link 44 with the connecting rod 38 and to the normally fixed pivot 45, this swinging movement of the connecting rod 38 causes the pivot point 43 to move in an arcuate path and this movement in turn causes endwise movement of the connecting rod 38, thereby imparting through the arm 41, a step-by-step intermittent rotary motion to the shaft 35. The amount of endwise rotary movement given to the connecting rod 38, and consequently the amount of angular movement given the shaft 35 for each rotation of the main shaft 15, is dependent upon the angular position of the anchor link 44. This position may be changed by shifting the feed-regulating bell-crank lever 49 about its pivot 50, thereby shifting the position of the normally stationary crank-arm 46 about its fulcrum. The above described mechanism for imparting an intermittent step-by-step movement to the shaft 35 and for varying the amount of movement is fully described in the Hacklander Patent No. 2,432,412, dated December 9, 1947, to which reference may be had for a more detailed disclosure.

Journaled in bearings 61 and 62 (Fig. 1) formed in the horizontal arm 32 is a driven shaft 63 which is arranged parallel to but substantially above the level of the stub-shaft 35. A belt pulley 64 grooved transversely of its circumferential face is connected by a belt 65 provided on its inner face with lugs adapted to enter the pulley grooves. This belt extends lengthwise through the forwardly extending arm and is in driving engagement with a similar pulley 66 secured to the shaft 63 adjacent the bearing 61; the pulleys 64

and 66 being of the same size. Secured to the shaft 63, adjacent the bearing 62, is another grooved pulley 67 of the same size as the pulley 66 and connected by a belt 68 to a grooved pulley 69 secured to a short feed-shaft 70 journaled in and extending transversely of the free end portion of the work-supporting arm 33. The feed-shaft 70 is disposed at substantially the level of the shaft 35, i. e., below the level of the shaft 63.

10 A feed-wheel 71 carried by the feed-shaft 70 operates through a slot 72 in a cover-plate 93 for the upper portion of the work-arm 33, and to intermittently advance the material M, cooperates with the usual presser-roller 73 carried by a spring depressed bar 73' journaled in the hollow-head 12.

15 Belt-tightening devices are provided for each of the belts 65 and 68. The belt-tightener for the belt 65 is located at the junction of the arms 31 and 32 and in close proximity to the pulley 66. As shown in detail in Fig. 5, it comprises a pulley 74 which engages the outer surface of the upper run of the belt 65, and is rotatably journaled on a shouldered bushing 75, fixed by a set screw 75', 20 on the eccentric portion 76, of an adjustable pin having an enlarged head 77 formed with a screwdriver slot and extending through a suitable aperture in the side wall 31A of the arm 31. The other end of the pin is formed with a reduced end portion 78 which is arranged concentric with the enlarged head 77 and enters a suitable aperture in the other side wall 31B of the arm 31 (Fig. 5). In order to prevent the pulley 74 from sliding laterally on the bushing 75, a collar 79 is secured by 25 a set screw 80 to the eccentric portion 76 of the pin adjacent the pulley 74. From the above it will be understood that the locking screw 81 may be backed off, the screw driver inserted in the slot in the head 74 and the pin turned so as to 30 adjust the eccentric portion 76 and pulley 74 relative to the belt 65.

35 The belt-tightener for the belt 68 is located at the junction of the arms 32 and 33 and in close proximity to the pulley 67. This belt-tightener is substantially the same as the one previously described and, as shown in Fig. 4, comprises a pulley 83 journaled on a bushing 84 carried by the eccentric portion 85 of an adjustable pin having an enlarged head 86 and a reduced end portion 87 40 rotatably mounted in the opposite vertical walls of the hollow work-supporting arm 33.

45 The elevated disposition of the shaft 63 in the raised carrier-arm 32, with respect to the levels of the shafts 35 and 70, provides for efficient operation of the belt-tighteners 74 and 83.

50 A lower stationary electrode 90 (Fig. 2) is mounted on an insulating block 91 secured on a lug 92 formed in the free end of the work-supporting arm 33. The electrode 90 extends through a suitable opening in the cover-plate 93 and 55 cooperates with an upper electrode 94 carried by the reciprocating bar 19. In order to provide a high-frequency field between the electrodes 90 and 94 a conventional high-frequency electron tube oscillator (not shown) operating at a frequency of from 30 to 100 megacycles is connected by a coaxial cable to a receptacle 96 (Fig. 1) secured to the arm 31.

60 The center post of the receptacle 96 is connected by a conductor 97 to one terminal of a variable condenser 98. The other terminal 101 of this condenser is connected to ground through the inductance coil 99 and conductor 100. Also connected to terminal 101 is the center conductor 65 102 of a coaxial cable 103 located in the hollow

horizontal arm 32 and terminating in the forwardly extending arm 33. The center conductor 102 at the terminating end of the cable is connected to a common junction of inductance 104, 104' mounted on an insulating block 105 carried by and located within the arm 33. Inductance 104' is connected to a common ground 106 with the outer conductor of the cable 103. Inductance 104 is connected to the lower electrode 90 by means of a conductor 107. As the machine frame 10 is grounded, the upper electrode 94 being in contact with said frame is also at ground potential and, therefore, a radio-frequency field is established in the region between the electrodes.

Having thus set forth the nature of the invention, what I claim herein is:

1. A machine for bonding together plies of dielectric material comprising, a frame having a standard carrying an overhanging bracket-arm terminating in a head and a bed including a supporting arm extending forwardly from the standard, a carrier arm extending laterally from said supporting arm parallel to said bracket-arm, and a work-arm extending from said carrier arm parallel to said supporting arm and having its free end disposed beneath said head, a first electrode reciprocably mounted in said head, a main shaft journaled in said bracket-arm, operative connections between said shaft and said electrode to impart reciprocation to said electrode upon rotation of said shaft, a second electrode carried at the free end of said work-arm and opposed to said first electrode, means for establishing a radio frequency field between said electrodes, a feed-wheel journaled in said work-arm on an axis transverse to the length thereof, a first pulley secured to said feed-wheel, and means for imparting intermittent rotary motion to said feed-wheel in timed relation to the reciprocation of said first electrode comprising a second pulley 40 journaled adjacent the base of said standard, an

intermediate shaft journaled longitudinally in said carrier arm, pulleys secured to the ends of said intermediate shaft, operative connections between said main shaft and said second pulley to impart intermittent rotation to said second pulley upon rotation of said main shaft, a first belt running longitudinally of the supporting arm entrained about said second pulley and the pulley on the adjacent end of the intermediate shaft, and a second belt running longitudinally of the work-arm entrained about said first pulley and the other pulley on the intermediate shaft.

2. A machine in accordance with claim 1 in which the bottom of said carrier-arm is disposed at substantially the vertical levels of the tops of the supporting arm and the work arm, and the axis of said intermediate shaft is disposed above the vertical levels of the axes of said first and second pulleys, when the machine is in operative position.

3. A machine in accordance with claim 2 provided with belt-tensioning means located adjacent the pulleys at the ends of the intermediate shaft, which means also serves to produce a change of direction of at least one of the belt runs of each belt.

HANS HACKLANDER.
